**COMBINED SEAT, BLACKBOARD AND TOY
HOLDER FOR A CHILD**

Natalie Mayer Gingold, 1525 E. 26th St.,
Brooklyn 29, N.Y.

Filed Apr. 7, 1964, Ser. No. 79,385

Term of patent 7 years

(Cl. D15—1)

FIG. 1 is a side elevation of a combined seat, blackboard and toy holder for a child, embodying my new design.

FIG. 2 is a view of the reverse side of the toy.

FIG. 3 is a top plan view of the same.

FIG. 4 is a front view of the combined seat, blackboard and toy holder for a child.

FIG. 5 is a view of the reverse end of the same.

FIG. 6 is a bottom view of the design.

The dominant features of my design reside in the portions shown in full lines on the drawings.

I claim:

The ornamental design for a combined seat, blackboard and toy holder for a child, substantially as shown and described.
